FREDRICK C. SMALSTIG, OF ALLEGHENY CITY, PENNSYLVANIA.

CIGAR-BUNCHING MACHINE.

SPECIFICATION forming part of Letters Patent No. 340,380, dated April 20, 1886.

Application filed December 19, 1885. Serial No. 186,186. (No model.)

To all whom it may concern:

Be it known that I, FREDRICK C. SMALSTIG, of Allegheny City, in the county of Allegheny and State of Pennsylvania, have invented 5 certain new and useful Improvements in Cigar-Bunching Machines; and I do hereby declare the following to be a full, clear, and exact description of the invention, such as will enable others skilled in the art to which it 10 pertains to make and use it, reference being had to the accompanying drawings, which form part of this specification.

My invention relates to an improvement in cigar-bunching machines; and it consists in, 15 first, the combination, in a bunching-machine, of the movable head, a connecting-rod, an operating-shaft provided with means for moving the said rod and head, the treadle for bringing the connecting-rod into operation, a 20 spring for returning the rod to position, and a second spring for returning the head to place; second, the combination of the movable head, the apron, the take-up lever, the guiding-pulleys, a connecting-rod, an operating-shaft provided with means for moving 25 the rod and the head, the treadle, and spring for returning the rod and the head to position; third, the combination of the head, the mechanism for operating it, the apron connected 30 directly to one end of the head, the rollers, and the curved spring-clamp having a recess in its end to receive the bunch; fourth, the combination of the movable head, devices for imparting to it an oscillating movement, the 35 apron, the roller under which the head is moved, the spring-clamp, a roller for engaging with the clamp and discharging the bunch, and a means for operating the roller; fifth, the combination of the movable head, the 40 apron, the guiding-roller, the flexible connections, the take-up lever, the connecting-rod, and a mechanism for imparting to the head an oscillating movement; sixth, the combination of the movable head, a mechanism for reciprocating it, the apron, and a suitable driving-pulley with a pivoted arm or lever which is connected to the head, the connecting-rod, a cut-off, and an ejector placed in the hopper; 45 seventh, the combination of the hopper, the 50 ejector placed therein, the movable back connected to the ejector and moved thereby, devices for connecting the ejector to the head,

the sliding knife, a spring actuated rod for operating the knife, a cord for connecting the rod to the head, the head, and a mechanism 55 for operating it; eighth, the combination of the head, a mechanism for moving it, the apron, the hopper, the ejector placed in the hopper and operated by the head, a cut-off, a mechanism for moving it, and a depositor provided with an arm which is moved by the head; ninth, the head, formed of two adjustable side pieces provided with flanges upon their inner sides, in combination with means for holding the heads in contact with the top; 60 tenth, the combination of the head, a mechanism for moving it, a flexible connection, the spring-actuated rod, the clamp connected thereto, the knife, the slide, the hopper, the ejector placed inside of the hopper, and the 65 set-screw for limiting the movement of the slide, all of which will be more fully described hereinafter.

Figure 1 is a vertical section of a machine embodying my invention. Fig. 2 is a similar 70 view showing the parts in their normal positions. Figs. 3, 4, 5, 6, 7, and 8 are detail views, and Fig. 9 shows a modification.

A represents a suitable inclosing-frame, which may be of any construction desired. 80 Journalized in one end of this frame, to the rear of the hopper, is the operating-shaft B, to which is secured the driven pulley C. Projecting from the inner side of this driven pulley C are two set-screws, D, which pass through 85 the slots E in the revolving disk F. This disk F is also provided with a slot at its center, so that it can be adjusted endwise upon the shaft B for the purpose of lengthening or shortening the stroke of the head which it is intended to operate. By means of these set-screws D this disk F is clamped rigidly against the side of the pulley C after it has once been adjusted in its proper position. The three slots 90 extending in the same direction and in a line with each other enable this disk F to be adjusted to any desired extent. Upon one side of this disk F is formed a projection, G, which, as the disk is caused to revolve with the pulley C, is made to engage with the pivoted rod H, which is pivoted at its inner end to the take-up lever I.

In order to depress the end of the rod H so as to bring it at that point where it will en-

gage with the projection G, the treadle J and the connecting-rod K are connected to the rod H near its inner end, as shown.

Secured to the inner end of the rod H is the spiral spring L, which throws the rod H up into the position shown in Fig. 2, where it will not be operated by the projection, except when it is desired that the movable head M shall be moved. Unless the operator depresses the treadle J, the head M will not be moved. Each time that the treadle J is depressed the head M is given a quick movement, so as to force it into position shown in Fig. 1, when the contact between the projection G and the end of the rod H ceases, and then the rod H is drawn back in position by means of the spring L, and the head M is drawn back in the position shown in Fig. 2 by the spring N, which is connected to its outside edge. The head M consists of the two side plates, which are clamped to the rod O, and which are held in any desired relation to each other by the clamping-rod W, which passes through one of the holes U', and by set-screws, which clamp the pieces to the rod O, as shown in Fig. 3. Each one of these side pieces of the head is provided with a flange upon its inner side, and upon which the top of the head is supported. This top is held by frictional contact between the two sides, and is made removable, so that heads of different kinds and different widths can be used. If so desired, the head can be made wide enough to use two aprons upon it, and then two bunches can be formed at the same time.

Rigidly secured to the rod O, to which the head M is fastened, is the take-up lever I, which is adjustably secured to the rod O by means of a set-screw. This lever I is provided with a series of holes near its upper end, so that the rod H can be connected to it at different points, and thus vary the amount of movement that shall be given to the head M at each stroke. Adjustably secured to the lower end of this rod I is a rod, P, and to this rod P are fastened the two clamps Q, by which the ropes R are held. These clamps Q can be turned in any position upon the rod P for the purpose of adjusting or tightening the ropes, wires, or other flexible connections at will. In case one of these connections R should become stretched or loosened in any way it can be quickly tightened by loosening the set-screw S, which passes through the clamp for the purpose of holding it. To the upper end of these connections there is fastened the rod T, which is laced or otherwise suitably connected to the apron U, as shown in Fig. 8. The two connections R pass around the guiding pulley or pulleys V, so as to cause the take-up lever I to take up all of the slack in the apron except that for receiving the loose tobacco and forming the bunch. No matter in what position the head is moved, the take-up lever I moves correspondingly and tightens the apron. This take-up lever I is longer than the head M, and the point at which the flexible connections R

are connected to the lever is farther from the center of motion than the top of the head, and hence, when the head M has completed its movement, as shown in Fig. 1, all of the slack of the apron is taken up. When the head returns to position, as shown in Fig. 2, and its top having moved a shorter distance than the point of contact for the connections R, enough slack is left between the inner edge of the head M and the guiding-roller W to form the pocket which is shown in Fig. 2, for the purpose of receiving the loose tobacco and the wrapper which is to form the bunch. 75 80

Connected to the head M, as shown in Figs. 1 and 2, is a flexible clamp, X, which catches the bunch as it is freed from the apron when the head reaches the end of its stroke, as shown in Fig. 1, and which clamp X holds the bunch between the outer edge of the head and its free upper end until the head M returns to the position shown in Fig. 2. The free end of this clamp X projects up above the outer edge of the head just far enough to engage with the corrugated roller Y, which is actuated by a cross-belt, Z, which runs from the pulley A' upon the shaft B. This roller Y is made to constantly revolve in the direction indicated, and as it engages with the clamp X 95 it forces it backward and upward sufficiently far to allow the movement of the head M to force the bunch in between the roller and the clamp, as shown in Fig. 2, when the revolutions of the roller Y cause the bunch to be ejected from the machine into any suitable receptacle placed to receive it.

Inside of the hopper B' is placed a false back, C', which is pivoted at its lower end to the ejector D'. This ejector D' is connected at 105 its rear end to a rod or shaft, E', to which the connecting-rod F' is secured, and which rod, at its lower end, is loosely attached to a rod, G', which is pivoted to the head M. Upon this rod G' are placed the two stops H', which regulate the distance the lower end of the rod F' shall move. Each time that the head is moved into the position shown in Fig. 1 the ejector D' is depressed, so as to force down a portion of the tobacco from the hopper B' 115 upon the bottom I', where it is held until the head M returns to the position shown in Fig. 2. The downward movement of the head M causes the free end of the ejector D' to be depressed by the rods F' G', connected to the head, and the return of the head to its normal position causes its free end to be raised upward by the same means, ready to force down another quantity of tobacco. 120

Upon the top of the frame A is placed a 125 sliding knife, J', which moves upon suitable guides, K', and connected to this knife J' on its under side is the slide L', which serves to force the tobacco which has been deposited upon the bottom I' off upon the automatic depositor M', where it is held during the downward movement of the head M. Connected to this knife J' and the slide L' is a spring-actuated rod, N', which carries an adjust-

able clamp, O', which is connected to it at any desired point. On this rod N' is placed a spiral spring, P', so as to return the knife and slide back to position as soon as the head M, to which it is connected by the flexible connection Q', is moved downward.

For the purpose of regulating the distance that the knife and slide shall be moved backward, a set-screw, R', is employed, as shown. 10 The outer end of the rod strikes against this set-screw when it returns to position, and thus limits the movement of the slide and knife.

The amount of tobacco which is to be forced forward upon the automatic depositor M' can 15 be regulated by adjusting the clamp O' by means of the scale which is secured upon the top of the frame. The automatic depositor M', shaped like a hinged door or drop, has a curved rod, S', secured to the lower side of its 20 free edge, and this rod is operated by the head M. When the head M is moved forward, as shown in Fig. 1, this rod S' slides over the top of the head until the head reaches the limit of its movement, and then returns back to 25 position, as shown in Fig. 2, and then the rod S' drops down behind the rear edge of the head and allows the automatic depositor M' to also drop and discharge the tobacco into the pocket of the apron. The wrapper is laid 30 upon this depositor M' by the operator, the treadle J is operated, the head moves, and then when the head returns to position the filler drops, and the wrapper and tobacco are dropped together in the apron U. The slack 35 in the apron is then closed by the movement of the head M at the next movement of the treadle J, and the bunch is rolled in the usual manner. A friction-roller, T', is used in connection with the roller W for the purpose of 40 preventing the apron from moving too freely, and to form the pocket in which the bunch is formed. The head M, in returning to position, moves with sufficient force to pull a suitable amount of the slack of the apron through 45 between the two rollers W T', and the slight backward movement of the head causes the excess of the apron which was drawn through between the rollers to form the pocket. In case it is not desired to fasten the flexible 50 connection Q' to the head M, it may be fastened directly to the pivoted rod or lever G', which will then move the knife and slide in the same manner as is here shown.

By means of the construction here shown, 55 it is only necessary for the operator to place the wrapper upon the depositor M', and then depress the treadle J so as to bring the rod H in contact with the projection upon the revolving disk, and then the whole operation of 60 the machine is performed by steam power, even to the ejecting of the bunch at the end of the movement of the head. The roller T' at the bottom of the hopper acts in connection with the knife J', which latter cuts off the 65 supply of tobacco from the hopper, and thus prevents any ragged pieces from hanging down

and clogging the action of the sliding knife. As the disk F revolves with great rapidity, the head M is caused to operate as rapidly as the operator can possibly place the wrappers 70 in position upon the depositor M'. In case it should be desired to give the head M a continuous motion regardless of any movement of the operator, it is only necessary to dispense with the treadle J K and spring L, then 75 make the rod H longer and connect one end of it to a crank or eccentric upon the shaft D and pivot its other end in one of the holes U' on the head, as shown in Fig. 9. The operation of the machine, with the exception that 80 the head is then given a continuous motion, will be exactly the same.

Having thus described my invention, I claim—

1. The combination, in a bunching machine, of a movable head, the connecting-rod H, the operating-shaft provided with means for moving the connecting-rod and head, the treadle for bringing the connecting-rod into operation, a spring for returning the rod to 90 position, and a second spring for returning the head to place, substantially as described.

2. The combination of the movable head, the apron, the take-up lever, the guiding-pulleys, the connecting-rod H, the operating-shaft provided with means for moving the rod and the head, the treadle, and springs for returning the rod and the head to position, substantially as set forth.

3. In a cigar-bunching machine, the combination of the head N, a mechanism for operating it, the apron connected directly to one end of the head, the rollers W T', and the curved spring-clamp X, having a recess in its end, so as to receive the bunch, substantially 105 as described.

4. The combination of the movable head, devices for imparting to it an oscillating movement, an apron, the roller under which the head is moved, the spring-clamp X, a 110 roller for engaging with the clamp and discharging the bunch, and a means for operating the roller, substantially as shown.

5. The combination of the movable head, a mechanism for imparting to it an oscillating 115 movement, the apron, the guiding-roller V, the flexible connection R, the take-up lever I, and connecting-rod H, the take-up lever being made longer than the head and to move a greater distance, substantially as described.

6. The combination of the movable head, a mechanism for reciprocating it, the apron, and a suitable guiding-pulley, V, with a pivoted arm or lever which is connected to the head, the connecting-rod, a cut-off, and an 120 ejector placed in the hopper, substantially as set forth.

7.. The combination of the hopper, the ejector placed therein, the movable back connected to the ejector and moved thereby, devices for connecting the ejector to the head, 130 the sliding knife, a spring-actuated rod for

operating the knife, a cord for connecting the rod to the head, the head, and a mechanism for operating it, substantially as specified.

8. The combination of the head, a mechanism for moving it, the apron, the hopper, the ejector placed in the hopper and operated by the head, the cut-off, a mechanism for moving it, and the depositor provided with an arm which is moved by the head, substantially as shown.

9. The head N, formed of two adjustable side pieces provided with flanges upon their inner sides, in combination with means for holding the heads in contact with the top, substantially as set forth.

10. The combination of the head, a mechanism for moving it, a flexible connection, Q', the spring-actuated rod N', clamp O', connected thereto, the knife J', the slide L', the hopper, the ejector placed inside of the 20 hopper, and a set-screw, R', for limiting the movement of the slide, substantially as specified.

In testimony whereof I affix my signature in presence of two witnesses.

FREDRICK C. SMALSTIG.
